UNITED STATES PATENT OFFICE.

FRANK PARDEE, OF HAZLETON, PENNSYLVANIA.

SPIRAL SEPARATOR.

1,356,464.

Specification of Letters Patent. Patented Oct. 19, 1920.

Application filed June 10, 1915. Serial No. 33,387.

To all whom it may concern:

Be it known that I, FRANK PARDEE, a citizen of the United States, and resident of the city of Hazleton, in the county of Luzerne and State of Pennsylvania, have invented certain new and useful Improvements in Spiral Separators, of which the following is a specification, reference being had to the accompanying drawings, forming a part hereof.

The invention relates to spiral separators of the class known to have a double pitch, that is, a downward pitch and a pitch toward the axis and which operate by gravity, centrifugal force and frictional resistance.

In spiral separators as heretofore constructed, no provision was made for protecting the central post nor for easing the transfer of coal from the separator thread to the outer or coal-thread of the machine.

The object of this improvement is to construct the spiral plates in such a manner as to avoid undue cutting or injury to the central post on the one hand, and, on the other, to transfer or lower the coal separated from the slate and bone to the coal-thread of the separator without undue fracture or breakage.

The present invention consists in forming the spiral plates which comprise the runway, with an inner upturned flange for placement next to the post and in forming certain plates with an outer downturned flange projecting from the slate-thread or so-called separator-thread, for lowering the coal to the coal-thread, as hereinafter more fully described.

In the drawings Figure 1, represents a right hand spiral separator having a slate or separator-thread, and a coal-thread, and shows a double feed chute at the top. Fig. 2, is a detail elevation showing the central post broken and the relative position of the plates composing the threads of the machine. Fig. 3, is a sectional detail through the plates and shows the positions of the supporting rods.

Fig. 4, is also a sectional detail in which the outer downturned flange is omitted from some of the separator plates, its projection and position being such as to transfer the coal directly to the coal-thread, while the bone, which is heavier, drops back into the separator-thread or a bone-thread, having no outer flange.

In these drawings A represents the central post and B, B', the feed chute at the top of the machine. These chutes connect with a source of supply not shown, but usually with a breaker chute which receives the sized mixed materials after they have passed through the screen or bars in the breaker. The materials to be separated pass from the feed chute B, B', into the separator thread composed of spiral plates A', A', preferably creased as indicated at a, a. The materials thus obtain a circular motion and during their passage down the slate-thread, the separation is effected by the differential action of gravity, centrifugal force and frictional resistance. The slate follows down or gravitates toward the post A, while the bone being next in weight and frictional resistance passes to the outer edge of the slate-thread or over the same into a bone-thread, and the coal owing to its lightness and smoothness moves with more rapidity under the influence of the centrifugal force, in an outward direction and is automatically transferred or delivered to the coal-thread.

The spiral plates A', A', are secured in position by bolts b, b, b, which pass through the rods b', b', b', the inner ends of which are fastened to the central post A. The floor or runway, plates A', A', of the separator thread may be creased as shown at a, a, for the purpose of affording retarding surfaces to the heavier materials, and they may also have overlaid perforated retarding plates a', a', which, as shown, cover only a part of the surfaces of the plates A', A'. At the lower end of the runway, the spiral plates are equipped with dividers or ridge plates A², A², which are adjustable and serve to deflect the outflowing materials to the chutes, not shown, for conveying them away after the separation has taken place. The plates A', A', of the separator-thread have an inner upturned flange a², next to the post and an outer downturned flange a³, which overhangs the bone or coal-thread, and some of these outer downturned flanges may be omitted as shown in Fig. 4.

The inner flanges of all plates come next to the post A, and form an inner hollow space which prevents the slate from crowding too much against the post and from cutting or wearing it unduly.

The outer downturned flange a³, of the separator-thread has a sufficient inclination

to lead the coal to a lower level and diminish the breakage by diminishing the distance of the drop which it makes in passing to the coal-thread. The coal-thread has an 5 outer upturned flange C, which may be separately formed or integrally formed as desired. The drawings show the outer flange as being formed separately from the floor or runway plates and secured to an upturned 10 bend in the rods b', b', by bolts b², b². This coal thread starts at a point determined by the spiral pitch and the downward and inward inclination of the separator thread, where the coal in its downward travel 15 acquires sufficient velocity to carry it beyond the outer edge of the separator thread or onto the inclined runway a³.

The upper portions of the separating runways are steeply inclined in the radial direction and have high vertical flanges on their outer edges, so as to prevent the escape of any material. In these portions of the separating runways the particles of coal are gradually separated from the others and accumulated on the outer portion of the runway. This separation is substantially completed in these upper portions and the character of the separating runways then changes by gradually bending the outer 25 flanges toward a horizontal direction, as at the left in the second convolution shown in Fig. 1, and finally outward and downward at a slight inclination to the horizontal as shown for the separating runways at the 30 right of the lowest convolution, so that the particles of coal previously separated and running down the outside of the runways is dropped comparatively gently from such runways; a supplemental runway being arranged 35 below the lower portion of the separating runway to catch the coal which drops from the outer edge thereof.

As the particles of coal run down the separating runway some of them strike 40 others and are liable to be projected inward out of their proper zone. Similarly particles of slate are liable to be projected outward into the proper coal zone, and over the edge of the separating runway into the supplementary runway designed for coal alone. The creased surfaces indicated at a extend 45 in an approximately spiral direction and tend to diminish this liability of improper admixture by maintaining each material in 50 its proper path.

Even without such knocking of the particles together, the weight and consequent centrifugal effect tends to throw the slate out beyond the edge of the separating run-

way. To prevent this the perforated plates 60 a' are used, giving a roughened surface which by taking advantage of the greater roughness of slate as compared with coal will permit the latter to pass outward and will hold the slate inward. To secure the 65 best results the surface should be roughened to cause the desired separation and should be creased to prevent subsequent accidental admixture, and I have provided for this by alternating the perforated plates and the 70 creased plates as indicated at the lower end of the separating runway.

In constructing a spiral separator with plates having inner or inner and outer flanges as described, such plates are formed 75 from suitable sheet or plate metal swaged into the required form and shape.

Having thus described the invention, what I claim as new and desire to secure by Letters Patent is:

1. A spiral separator comprising a coal-thread and a separator-thread having runways composed of spiral plates, the floor-plate of said separator-thread being provided with outer flanges turned downward 85 at a slight inclination to the horizontal for aiding in lowering the separated coal gently to said coal-thread.

2. A spiral separator comprising a coal-thread and a separator-thread, said last 90 mentioned thread being composed of runway plates having an outer flange turned downward at a slight inclination to the horizontal and with retarding surfaces whereby the rougher substances may be separated from 95 the smoother ones and the latter delivered to said coal-thread.

3. A spiral separator comprising a spiral separating runway having at an upper point 100 a downward and inward inclination throughout its width, said spiral runway having its width at a lower point composed of a downwardly and inwardly inclined inner portion and a downwardly and outwardly inclined outer portion.

4. A spiral separator comprising a pair of separating runways, one above the other, and a supplementary runway below them to receive material escaping outward therefrom, the upper one of said separating runways having an outer flange turned downward at a slight inclination to the horizontal for delivering said material comparatively gently to said supplementary runway.

FRANK PARDEE.
